SAFETY MECHANISM FOR ELEVATORS.
APPLICATION FILED OCT. 20, 1919.

Patented Aug. 3, 1920.

2 SHEETS—SHEET 2.

UNITED STATES PATENT OFFICE.

CARL POSEY BEAVER, OF DUCKTOWN, TENNESSEE.

SAFETY MECHANISM FOR ELEVATORS.

1,348,201.

Specification of Letters Patent.

Patented Aug. 3, 1920.

Application filed October 20, 1919. Serial No. 331,822.

To all whom it may concern:

Be it known that I, CARL POSEY BEAVER, a citizen of the United States, residing at Ducktown, in the county of Polk, State of Tennessee, have invented certain new and useful Improvements in Safety Mechanism for Elevators; and I do hereby declare the following to be a full, clear, and exact description of the invention, such as will enable others skilled in the art to which it applies to make and use the same.

This invention relates to safety devices for elevators.

The object of the invention is to improve the structure of safety devices for elevators, the improvements being wrought in that type of safety devices in which the safety clutch members or stops are held out of engagement when the elevator cage is suspended from the cable, but are released into stopping position when the cable breaks so that the weight of the cage is not carried thereby. The invention resides, not only in the provision of the improved clutch releasing mechanism, but in the clutch members themselves and the manner in which they are mounted.

With the above objects, in view, and such other relating to the details of construction as may hereinafter appear, my invention will now be fully set forth and described, reference being had to the accompanying drawings.

In the drawings:

Fig. 1 is an elevation disclosing the general assemblage of the mechanism,

Fig. 2 is a vertical section on line 2—2 of Fig. 1,

Fig. 3 is a section on line 3—3 of Fig. 1,

Fig. 4 is a section on line 4—4 of Fig. 1,

Fig. 5 is a section similar to Fig. 4, but showing the parts in closed position,

Fig. 6 is an enlarged detail perspective view,

Fig. 7 is a further detail view and

Fig. 8 is another detail view.

Referring more particularly to the drawings, 1 represents the rails upon which the cage 2 of a mine elevator operates. The cage 2 may operate in either a vertical or an inclined shaft, but the elevator construction upon which the invention has been shown in the present instance, is that which is particularly adapted for use in inclined shafts. Therefore, the car 2 is supported upon the rails 1 by means of rollers or wheels 3.

Mounted upon the side of the car which spans the rails 1 is a rack bar 4 which is longitudinally movable, to a limited degree, within guide members 5 secured to the car 60 or cage body. The lower end of the rack bar 4 is connected to one end of a comparatively heavy spring 6 whose opposite end is secured to a base bracket 7 mounted against the side of the car. The opposite end of 65 the rack bar 4 is pivotally connected to one end of a lever 8 which extends across the upper end of the cage, and has its opposite end pivotally mounted in a pivot block or bracket 9 secured upon the cage. At an intermediate point on the lever 8, a swivel 10 is provided to which the elevator cable 11 is secured. The tendency of the cable 11, when it is tensioned to lift the cage, is to draw the rack bar upwardly against the tension of the spring 6 until a balance of the forces has been struck. Mounted in outer brackets or bearings secured to the side of the cage is a shaft 12 which extends transversely of the rack bar 4 and has a pinion 70 13 which meshes with the teeth of the rack bar. Also mounted upon the shaft 12 are the worms 14 which mesh with worm gears 15 mounted upon the upper ends of the shafts 16. Said shafts 16 are carried in bearings 75 17 disposed at practically equal distances from opposite sides of the rack bar, so that the shafts 16 substantially parallel the latter.

Surrounding the shafts 16 are the coil springs 18. Preferably, there are two 90 springs to each shaft, one end of each of the springs being connected to its respective shaft and the opposite end being fixed to one of the brackets or bearings 17 or to another bracket secured to the side of the cage. The 95 tendency of the springs is to turn the shafts 16 in a direction opposite to the direction of rotation imparted by the worms 14 to the worm gears 15.

Mounted in guide ways 19 which are also 100 secured in a suitable manner to the side of the cage 2 are the horizontally or transversely slidable clutch frames 20 and 21 upon which are formed the clutch elements 22 and 23 respectively, the clutch members 105 22 being adapted to grip the inner sides of the rails while the clutch members 23 are oppositely disposed to clutch the outer sides of the rails opposite the members 22. The clutch members 22 and 23 may have gripping faces of any suitable form, series of teeth being indicated in the present instance

for taking hold of the faces of the sides of the rails. The clutch frames 20 and 21 are connected in pairs to the shafts 16 by means of the devices which tend to throw the members of the pairs in opposite directions so as to close or open them simultaneously. Thus, upon each of the shafts 16 there are secured sets of eccentrics 24 and 25. The eccentrics 24 extend inwardly from the shafts, with respect to the rails, and are surrounded by eccentric straps 26 carried by the frames 20 so that rotation of the shaft 16 tends to throw the frames 20 outwardly. The sets of eccentrics 25 extend outwardly or in the opposite direction from the eccentrics 24, so that as the shafts 16 are rotated, eccentric straps 27 which are carried by the frames 21 and surround the eccentrics 25 tend to draw the clutch members 23 inwardly into engagement with the rails simultaneously with the outward movement of the clutch members 22.

In the use of the clutch mechanism which has been described, the parts are held in a normally inoperative position by the tension of the weight of the cage which is suspended from the cable 11, since the upward pull of the cable lifts the lever 8 and with it the rack bar 4. When the rack bar 4 is lifted, the pinion 13 is rotated to operate the worms 14 with result that the shafts 16 are rotated against the tension of the springs 18. This rotation of the shafts 16 separates the clutch members 22 and 23 so that they clear the rails. The lift of the cable 11 draws the rack bar 4 upwardly against the tension of the spring 6, so that when the cable 11 is untensioned, or broken, the spring 6 immediately draws the rack bar downwardly into its normal position, with the result that the shafts 16 are released to the tension of the springs 18, and are also aided in their return rotation by the motion communicated to the rack bar through the gears 13, 14 and 15. The immediate result of this action is to throw the clutch members 22 and 23 into engagement with the rails so that the car is stopped thereby within a few inches of travel.

It will be apparent from the foregoing description that the clutch mechanism constitutes a very simple gripping means for stopping a car or cage after its hoisting cables have parted, and that furthermore the mechanism in addition to its simplicity, will act positively and with sufficient strength to stop the car even though the latter were traveling with considerable momentum at the time the break occurred.

What I claim as my invention is:—

1. A safety mechanism for elevators, comprising a longitudinally movable rack bar, a pair of shafts paralleling said rack bar, means gearing said rack bar to the shafts, to rotate the latter, clutch members ar-

ranged to grip the elevator rails, and means operated by the rotation of the shafts to close the clutch members over the rails.

2. A safety mechanism for elevators, comprising a longitudinally movable rack bar, a pair of shafts paralleling said rack bar, means gearing said rack bar to the shafts to rotate the latter, clutch members arranged to grip the elevator rails, and means pivotally supporting the clutch members on the shafts in such relation that rotation of the latter closes the clutch members on the rails.

3. A safety mechanism for elevators, comprising a longitudinally movable rack bar, a pair of shafts paralleling said rack bar, means gearing said rack bar to the shafts to rotate the latter, clutch members arranged to grip the elevator rails, and eccentric supports on the shafts and carrying the clutch members so that rotation of the former closes the latter on the rails.

4. A safety mechanism for elevators, comprising a longitudinally movable member, a pair of shafts paralleling said member, means connecting said member to the shafts to rotate the latter, clutch members arranged to grip the elevator rails, and means operated by the rotation of the shafts to close the clutch members over the rails.

5. A safety mechanism for elevators, comprising a longitudinally movable member, a pair of shafts paralleling said member, means connecting said member to the shafts to rotate the latter, clutch members arranged to grip the elevator rails, and means supporting the clutch members on the shafts in such relation that rotation of the latter closes the clutch members on the rails.

6. A safety mechanism for elevators, comprising a longitudinally movable member, a pair of shafts paralleling said member, means connecting said member to the shafts to rotate the latter, clutch members arranged to grip the elevator rails, and eccentric supports on the shafts and carrying the clutch members so that rotation of the former closes the latter on the rails.

7. A safety mechanism for elevators, comprising in combination, a longitudinally movable member, a means normally holding said member at one limit of its movement, means to connect a hoisting cable to the member to move the latter against said holding means, a pair of shafts paralleling the movable member, means gearing said member to the shafts to rotate the latter when it is longitudinally moved, and clutch members arranged to grip the elevator rails and connected to the shafts to close when the tension of the cable is released to permit the return of the member to normal position.

8. A safety mechanism for elevators, comprising in combination, a longitudinally movable member, a means normally holding

said member at one limit of its movement, means to connect a hoisting cable to the member to move the latter against said holding means, a pair of shafts paralleling the 5 movable member, means gearing said member to the shafts to rotate the latter when it is longitudinally moved, clutch members arranged to grip the elevator rails and connected to the shafts to close when the 10 tension of the cable is released to permit the

return of the member to normal position, and resilient means normally tending to rotate the shafts into clutch opening position.

In testimony whereof, I affix my signature in the presence of two witnesses.

CARL POSEY ^{his} X BEAVER.
